UNITED STATES PATENT OFFICE

121,305

DESIGN FOR A MAGAZINE HOLDER

Joel W. Ostrander, Chicago, Ill., assignor to Hughes Loose-Leaf Metals Company, a corporation of Illinois

Application April 24, 1940, Serial No. 91,922

Term of patent 7 years

To all whom it may concern:

Be it known that I, Joel W. Ostrander, a citizen of the United States, residing at Chicago, county of Cook and State of Illinois, have invented a new, original, and ornamental Design for a Magazine Holder, of which the following is a specification, reference being had to the accompanying drawing, forming a part thereof, in which:

Figure 1 is a top plan view of the article, showing my design; and Figure 2 is a side elevational view of the same.

I claim:

The ornamental design for a magazine holder, as shown.

JOEL W. OSTRANDER.
